UNITED STATES PATENT OFFICE.

RICHARD H. CUNNINGHAM, OF NEW YORK, N. Y.

COMBINED IGNITION SYSTEM.

1,026,565.

Specification of Letters Patent. Patented May 14, 1912.

Application filed April 28, 1910. Serial No. 558,442.

To all whom it may concern:

Be it known that I, RICHARD H. CUNNINGHAM, a citizen of the United States, residing at the city of New York, in the borough of Manhattan and State of New York, have invented certain new and useful Improvements in Combined Ignition Systems, of which the following is a full, clear, and exact description.

10 This invention relates to combined ignition systems, and more particularly to such a system comprising a self-contained, high tension, stationary inductor to be used in combination with internal combustion engines for effecting ignition therein.

15 The object of the present system and the devices comprised in the same is to fire the charge of explosive gas in an engine when the latter is at rest, causing a spark to be produced by making circuit from a suitable external source of current, such current being delivered through the coöperation of suitable devices in such manner as to effect the production of a plurality of current impulses whereby to cause a torrent of sparks in the cylinder or like part of the engine.

20 In my device, the current from said external source invariably passes through a stationary winding of said inductor in such manner that demagnetization of the poles thereof or a reversal of polarity is substantially impossible when the rotatable armature of said inductor is in its usual resting position, and when properly timed with respect to the usual upright four cylinder four cycle engine.

25 A further object is to not alone prevent demagnetization of the said inductor poles, but to actually serve to strengthen the permanent magnetic field; further, to so conduct the current from the external source which in this instance is a battery, through the said stationary coil, when at very low speeds, as for example when starting engines of large compression, that the auxiliary current may augment or boost that of the inductor, and on being interrupted will produce powerful secondary sparks in the engine cylinder at exactly the correct moment.

Other objects of my invention will be hereinafter set forth and particularly pointed out in the appended claims.

Referring to the drawings which form a part of this disclosure: Figure 1 diagrammatically illustrates the several parts and

connections therebetween. Fig. 2 is a fragmentary section of the extremity of the inductor shaft. Fig. 3 is a perspective view of a modification of the inductor.

In the particular embodiment of my invention herein shown, the inductor alternating generator 1, shown in Fig. 1, comprises a four pole rotor, although it is obvious that a greater or less number of poles may be used if desired. The north and south poles of the stator have respectively been designated 2 and 3. These poles are disposed with respect to the rotary armature at 90° apart; and the armature or rotor comprises a soft iron cylindrical central member or core 5, and end portions 6, which portions are preferably of laminated soft iron. The two laminated members or portions 6 are disposed at opposite ends of the core 5, and substantially at right angles to each other. This construction affords a reversal of the lines of force in the armature for every 90° of rotation of the same. The inductor-generator will hereinafter be referred to simply as the inductor and has a primary winding 7 and a secondary winding 8. Both windings are preferably fixedly mounted in suitable extensions 9 which are carried by the respective poles of the inductor. These extension pieces as shown are somewhat U-shaped in cross section, and may be made of brass, if so desired; or if not carried into too close proximity to the core 5, may be made of iron. A shaft 10 extends outwardly from and in alignment with the axis of core 5, and carries thereupon a four part commutator 11, the respective sets of segments 12 and 13 of which are properly insulated from each other by means of insulating strips 14 which may be of fiber or other suitable material. Brushes 15 and 16 are insulatedly mounted as shown, and are disposed with respect to each other at substantially 90°. The armature is adapted to rotate counterclockwise as indicated by the arrow 17, and the winding of the primary wire is such that when said armature is so rotated with the permanent poles disposed as shown, current will traverse the lead 18 from said primary winding in the direction of the arrow shown in connection with said lead. Owing to the presence of the commutator and the particular arrangement thereof, the direction of the induced current is reversed periodically every 90° of rotation of the armature, so that the current deliv-

ered is an unidirectional, pulsatory one. The secondary is as aforesaid also preferably stationary, and is connected in series with a suitable distributor 19' which may be 5 of any well known type; one lead 19 of the secondary being grounded as indicated, and the other being connected to the usual distributing sector 20' of the distributor.

The commutator segments 13 are electrically connected to each other and by means of a lead 20, to an insulatedly mounted conducting member 21, carried by the inductor shaft. The extremity of the shaft has been shown in Fig. 2, wherein said lead 20 extends 10 down through an insulating sleeve 22 which extends out laterally through the shaft 23 and a corresponding sleeve 24 extends axially of said shaft and carries therein the conductive member 21. The second 15 set of segments 12 of the commutator, if a four part commutator be used, are grounded to the shaft at 26. An economizer box 27 of substantially the same general construction as has been described in my co-pending application Serial No. 540,781, filed Jan. 29, 1910, is disposed so that the extremity of the shaft carries thereupon the breaker box cam 28, which may be of fiber or other suitable material and this cam is substantially similar to that described in the said companion application. In this instance, however, cam 28 is so formed that it is adapted to break circuit between the contact points 29 and 30 every half revolution of the shaft; such circuit being kept open during approximately one quarter turn of the shaft. The breaking of contact as aforesaid, is effected through the lifting of the lever 31, said lever carrying a roller 32 which is so disposed as to 25 contact with the extended portions of cam 28. The lever 31 is pivotally connected at 33 to the casing of the breaker box, and it may be here observed also that the lever is grounded to the said casing at this point. 30 A bracket 34 is mounted upon one side of the interior of said casing, and is properly insulated therefrom by means of fiber strips or the like, and this bracket carries a suitable adjusting screw 35, the upper end of which forms contact 30. Contact 29 is carried upon the free end of lever 31. Brackets 36 and 37 are mounted substantially opposite to the bracket 34 and are so disposed with respect to each other that two springs 38 and 39 which are respectively carried by brackets 36 and 37 may normally maintain contacts 40 and 41, which are respectively carried upon the ends of springs 38 and 39, just out of contact with each other. Button 42 is disposed upon the upper side of the extremity, for engagement with cam 28, and this button is so disposed with respect to said cam and to roller 32 that contact will be made between the contact points 40 and 45 41 only an instant prior to the breaking of

contact between contact points 29 and 30. It follows from this action that when the engine is in operation and the battery is thrown into circuit, the current is only permitted to flow from the battery for a very short period during each half revolution of the shaft 10. The purpose of this arrangement has been more particularly set out in my co-pending application aforesaid. A suitable brush is provided for taking current off from the end of the conductor 21 carried in the interior of end of shaft 10, and a lead 43 extends from this brush to a contact 44 carried by the frame of a suitable switch. The remaining contacts of this switch may 50 be here considered, there being six of such contacts altogether, namely, 46, which is disposed adjacent to 44; 47 and 48 which are adjacently disposed with respect to each other, and 49 and 50, these latter constituting the contacts for throwing the battery into circuit. The switch blades 51 and 52 are disposed one upon either side of a pivoted insulating block 53; 51 being carried by the under side of said block, and 52 correspondingly by the upper side. The switch is normally adapted to be disposed in one of two positions, namely, that marked "Bat.", and in which position the switch is shown in Fig. 1, and that designated 55 "Inductor".

A suitable battery 54 is indicated in Fig. 1; and a button switch 55 is indicated in the upper portion of said figure; two sets of contacts being operated successively when 100 the button 56 of said switch is depressed. This button is supported in any suitable manner, and when depressed, the under side thereof engages a resilient element 57, thereby breaking contact between a point 58 carried by said element, and a corresponding contact point 59 which is fixed to a permanently disposed switch element 60. A second resilient element 61 which carries a contact 62, is adapted to be placed in electrical 105 communication with a resilient element 63, which carries a contact 64; the action of the button being such that when depressed, contact between points 58 and 59 is broken, and at the same instant, or practically at the 110 same instant, contact is made between the point 62 and 64.

A vibrator is shown at 65, wherein the usual electromagnet 66 has disposed thereupon a suitable conductive coil 67, and also carries a light trembler spring 68 which is disposed in electrical contact with the core of the magnet. The spring 68 carries the armature 69 and a contacting lug 70 which is engageable with a suitable screw 71. A lead 125 72 connects the adjustable screw or stud 71 with contact 49 of the switch; current from said lead traversing the stud 71, lug 70, spring 68 and one end of the core, and thence through the coil 67 disposed thereon. 130

A suitable condenser 73 is interposed in parallel across the break in circuit, being connected respectively to conductor 72 and coil 67. We may now consider the various 5 remaining connections. Assuming that the switch is disposed in its battery position and that the engine is not being turned, but that it is desired to start the same from button 56. The engine is in this instance, for example, a four cylinder engine, and one of the cylinders thereof should have come to rest with the proper explosive mixture therein, the same being under compression. The distributor will effect the distribution 10 of the spark to the proper cylinder in the usual manner; so this feature need not be further herein referred to. Considering now that conditions are as above stated, upon pressing the button 56, current will 15 flow from the positive pole of the battery up through lead 74 to contact 50, then through segment 51, to contact 49, through conductor 72 to stud 71, thence through the vibrator and its coil, and conductor 75 to element 63 of the button switch. As contacts 62 and 64 are closed, the current will 20 then proceed therethrough and down through conductor 76 to ground at 76'. As the commutator segments have correspondingly 25 stopped in a substantially predetermined position, the current will be able to flow from ground at 26 through to segment 12, which is in communication with insulated brush 15. Current will flow thence 30 through connection 79 to the primary coil 7, around the same, and thence through wire 18 to brush 16, commutator segment 13, connection 20, thence out at 21 into wire 43, contact 44, connection 45, contact 48, switch 35 segment 52, contact 47, and around through wire 78, to the negative pole of the battery. This is the only path available to current 40 under these conditions, since contacts 58 and 59, will, when the button 56 is depressed, be open. Considering now the battery circuit, when button 56 is in its upper position, not being depressed, but while the engine is being cranked, the gas being insufficiently compressed in any of the cylinders to enable 45 the engine to start on the button;—current will flow from the positive pole of the battery to the following connections and parts, which will be designated in most instances by number,—74, 50, wire 79, 58, 59, 60, connection 80, insulated stud 81, which is carried by the lower portion of the breaker box 50 casing, connection 82, bracket 37, thence through 39, 41, 40, 38, through connection 83, 35, 39, 29, 31, to ground, to 26, to 12, thence to 15, 79, through primary coil 7, 18, 16, 13, 20, 21, 43, 44, 45, 48, 52, 47, 78, and back to the negative pole of the battery. Considering now the course of current 55 through the circuit when the switch is in the position marked "Inductor." The bat-

tery will now be out of circuit and current will proceed from the primary coil of the inductor through 18, 16, 13, 20, 21, 43, 44, 51, 46, wire 77, stud 78' (which is insulated from the breaker box casing, but is connected to bracket 34) 34, 30, 29, 31, to ground, to 26, thence to the primary coil of the inductor. The circuits have been respectively designated by arrows in order to show the direction of current through the wires of the several circuits, an arrow unaccompanied by any letter indicating that current will flow through that particular lead or conductor under all conditions if any current whatsoever be flowing through the device. An arrow having B alongside thereof, designates a conductor carrying current from the battery when the button 56 is depressed; an arrow having C alongside of the same correspondingly designating current from the battery when the engine is being cranked. Finally, an arrow with M beside it designates current from the inductor. It is thought that this arrangement will render the several circuits more clearly readable at a glance. Arcing at the contacts 29, 30 is prevented, no matter whether current flows through the stationary primary coil of the inductor from battery, while cranking, or whether current be drawn from the inductor; this being accomplished by placing stud or binding post 78' directly in connection with a suitable condenser 84, the other side of which condenser is connected to ground at 85. This places 60 condenser 84 directly across the point of rupture of the current. In connection with the changing polarity of the revolving armature, it is to be observed that the circuit through the primary winding is broken shortly after the edge of the armature leaves the pole piece, and that this circuit stays open until the armature has revolved through substantially 90°. The width of the insulation 14 which is provided between the commutator segments is slightly greater than the width of the brushes, so that by no possibility can the battery be short-circuited therethrough; and it is further desirable to so arrange the position of the commutator 65 parts with respect to the cam 28, that no current can flow through the circuits at the instant when the commutator segments are leaving the brushes, and hence the only wear upon the switch parts is due to friction alone; arcing at the brushes being impossible. In this as in my preceding system, there can be practically no waste of battery current, nor can there be any over-heating or burning out of the primary winding of the inductor, whether the engine be at rest or in motion. I particularly wish to call 70 attention in connection with this arrangement of my apparatus to the provision of the vibrator, by means of which it becomes 75

possible to maintain the button in its depressed condition for any desired length of time without materially wasting current from the battery, and at the same time producing in manner above described, a torrent of sparks in the proper cylinder. The combination of the button switch shown with the remaining parts of my device is also believed to be novel, in that when it is depressed current is obtained from the battery and the induced current is delivered in the manner aforesaid in high tension oscillatory form to the proper cylinder, while when the button is not so actuated, a circuit is established whereby upon cranking the cylinder, battery current may be used to the same end. Finally, I wish particularly to direct attention to the novel arrangement of parts herein presented, which involves the use of an inductor. All parts of the said inductor, including the primary and secondary windings are stationary, except the rotatable armature. By reason of this construction, I have virtually provided a stationary induction coil which serves in combination with the battery to attain the results usually obtained from induction coils. This coil is not alone an induction coil in the ordinary sense, but further constitutes the primary and secondary coils of a rotatory inductor, and is usable in connection therewith by reason of the provision of a commutator and its insulated brushes, and when the armature of the inductor is not being rotated connections are nevertheless established for using the said coils as an ordinary induction coil in the manner aforesaid. There is of course the further advantage in this construction that as herein presented there need be practically no moving wires, whatsoever in the system.

It is obvious of course that the inductor may be of other types than that shown in Fig. 1, and I have illustrated a modification thereof in Fig. 3, wherein the stator poles are disposed 180° from each other and the rotor is of a two pole type, comprising a core with end pieces or poles 6' at either end thereof, projecting in opposite directions. The commutator 11 in this instance comprises two segments one of which is connected to ground at the shaft and the other to a conductive member axially disposed in the shaft, in the manner shown in Fig. 1. The circuit connections are practically identical with those previously described. One of the principal advantages to be derived from using an inductive alternating generator in place of a generator of the type described in my previously filed application is that a much higher voltage may be obtained in the secondary for a given size of generator; the stationary winding permitting of a greatly increased number of secondary turns. It should be here noted,

however, that there is also a peculiar co-action between the inductor-generator and the other parts of my system. In action this type of generator tends to destroy its permanent field; the rotor reacting deleteriously upon the stator poles. Now as my apparatus as previously described contemplates not alone a boosting action by the battery current upon the generator current, but in use actually strengthens the permanent field of the inductor; this counter-balances the deleterious action above described and maintains the generator at its limit of efficiency. As a matter of interest in this connection, I find that it is actually unnecessary to initially magnetize the stator parts, since they will be properly magnetized by merely starting from a suitable battery. This conclusively demonstrates the value of my arrangement, and as aforesaid, its peculiar applicability to a system comprising an inductor alternating generator; the combination of parts above described insuring the continued production of sparks of relatively great length.

Having thus described my invention, what I claim is:

1. In a combined ignition system, a magneto having a plurality of poles, and primary and secondary windings, a commutator having a plurality of segments, means for affording connection between a primary winding of said magneto and at least one of said segments, circuit breaking means in circuit with said primary winding and normally in contact when the magneto is at rest, an external source of current, a switch for cutting said external source of current into or out of circuit with said primary winding, as desired, vibratory means adapted to be placed in circuit with said primary winding and said external source of current, and an auxiliary normally open contact-making device in circuit with the external source of current, current flowing through said vibratory means and through the primary winding aforesaid from said external source only when said device is actuated by the operator.

2. In a combined ignition system, a magneto having an armature and primary and secondary windings, a distributor in circuit with said secondary winding, an external source of current, means for throwing said source of current in circuit with a primary winding of said magneto, a commutator in said circuit, and a breaker box comprising means for automatically and periodically interrupting current through said primary winding, regardless of the source of current therethrough, said box further comprising additional periodically actuated circuit breaking and making contacts for economizing the flow of current from said external source when the latter is in circuit, the

periodicity of actuation of said contacts being the same as that of the periodic circuit interrupting means aforesaid but of different phase.

- 5 3. In a combined ignition system, a magneto having primary and secondary windings, a commutating device, means for affording connection between a primary winding of said magneto and a part of said commutating device, an external source of current, and a plurality of circuit making devices at least one of which is normally closed and another of which is normally open, connections between said external source of 10 current and said devices, and between some of said devices and said primary winding, and means for opening one of said normally closed circuit making devices whereby one of said normally open circuit making devices which is in circuit with said primary winding may be cut out of circuit, said means substantially simultaneously closing another of said devices of the latter type, and means for causing pulsations in the current from said external source.
- 15 4. In a combined ignition system, a magneto having primary and secondary windings, a commutating device, means for affording connection between a primary winding of said magneto and a part of said commutating device, an external source of current, and a plurality of circuit making devices at least one of which is normally closed and another of which is normally open, connections between said external source of 20 current and said devices, and between some of said devices and said primary winding, and means for causing pulsations in the current from said external source.
- 25 5. In a combined ignition system, a magneto having a primary winding, a commutating device, an external source of current, a plurality of automatic contact-making devices, means for successively actuating said devices in accordance with the movement of the magneto armature shaft, a switch having two positions, electrical connections between said primary winding, one of said contact-making devices and said switch forming a circuit including such parts when the switch is in one position, and additional connections electrically uniting another of said contact-making devices, the switch and the external source of current, said last mentioned connections coöperating with the connections aforesaid to form a circuit including said primary winding, second contact-making device, external source of current 30 and the switch when the latter is in its second position.

and means for opening one of said normally closed circuit making devices whereby one of said normally open circuit making devices which is in circuit with said primary winding may be cut out of circuit, said means substantially simultaneously closing another of said devices of the latter type, and a vibrator in circuit with said external 40 source.

5. In a combined ignition system, a magneto having a primary winding, a commutating device, an external source of current, a plurality of automatic contact-making devices, means for successively actuating said devices in accordance with the movement of the magneto armature shaft, a switch having two positions, electrical connections between said primary winding, one of said contact-making devices and said switch forming a circuit including such parts when the switch is in one position, and additional connections electrically uniting another of said contact-making devices, the switch and the external source of current, said last mentioned connections coöperating with the connections aforesaid to form a circuit including said primary winding, second contact-making device, external source of current 50 and the switch when the latter is in its second position.

In witness whereof, I subscribe my signature, in the presence of two witnesses.

RICHARD H. CUNNINGHAM.
